Primary Examiner — Sharon S Oum*Assistant Examiner* — Vanessa Martinez(74) *Attorney, Agent, or Firm* — Harness, Dickey & Pierce, P.L.C.(57) **CLAIM**

The ornamental design for an LED lamp as shown and described.

DESCRIPTION

FIG. 1 is a front elevational view of an LED lamp showing our new design; and,

FIG. 2 is a front perspective view thereof.

The broken lines in the drawings show portions of the LED lamp that form no part of the claimed design.
